UNITED STATES PATENT OFFICE.

DANVILLE W. STARRETT, OF OAKLAND, CALIFORNIA.

LIQUID-IMPELLING APPARATUS.

No. 821,677.

Specification of Letters Patent.

Patented May 29, 1906.

Application filed June 12, 1903. Renewed November 20, 1905. Serial No. 288,273.

To all whom it may concern:

Be it known that I, DANVILLE W. STARRETT, a citizen of the United States, residing at Oakland, in the county of Alameda and State of California, have invented certain new and useful Improvements in Liquid-ImPELLING APPARATUS, of which the following is a specification.

My invention relates to compressed-air pumps, the object of my invention being to provide an apparatus of this character by which water or other liquid can be raised or propelled to a greater height or to a longer distance than heretofore without proportionately increasing the pressure of the compressed air which is used for that purpose, thereby effecting economy in the strength of the pipe and other apparatus used for conducting the water or other liquid and also in the power for compressing the air; also effecting economy by the avoidance of undue heat due to the great compression which the air would otherwise have to undergo.

In the accompanying drawings, Figure 1 is a front view of one form of the apparatus. Fig. 2 is a side view, on an enlarged scale, certain parts being broken away. Figs. 3 and 4 are views similar to Figs. 1 and 2 of a modified form of the invention. Figs. 5 and 6 are horizontal sections on the lines *a a b b* of Fig. 4. Fig. 7 is a vertical section of an experimental device illustrating the principles of the invention.

Referring to the drawings and considering first the modification illustrated in Figs. 1 and 2, 1 represents a double-acting air-compressor having a piston 2. Spring-controlled valves 31 are provided to allow a certain proportion of air to be supplied to the air-compressor from the outside. This is necessary to take the place of the air which escapes up the discharge-pipe. From said compressor lead pipes 3, opening at the bottom into the lower ends of receivers 4. 5 represents the suction-pipe having branches 6 connected with the receivers 4. Check-valves 7 are provided at the bottoms of said receivers. From the tops of the receivers 4 lead the branches 8 of the water-discharge pipe 9, there being also check-valves 10 at the tops of the receivers. From the compressed-air pipes 3 short pipes 11 conduct to the branches 8, having therein the check-valves 12.

55 In the modification shown in Figs. 3 to 6 the two air-pipes 3 connect with a single pipe

13, which is conducted down in the interior of the water-discharge pipe 14. There is provided at the juncture of the pipes 3 and 13 a valve 15, which is automatically actuated by the movement of the piston, through a lug 16 reciprocating therewith, to disconnect the pipe 13 from one of the air-pipes 3 and connect it with the other, thereby first exhausting the air in the pipe 13 until the piston has traveled a portion of its stroke and then shutting off the exhaust and forcing compressed air into the pipe 13. The pipe 13 at its lower end is connected with a conduit 17, formed integral with the top 18 of the receiver 19, said receiver having also a compressed-air conduit 20 formed integral therewith and discharging at the bottom thereof, as shown at 21. 22 is a suction-pipe for supplying said receiver with water, and 23 and 24 are the check-valves at the upper and lower ends of said receiver, corresponding to the check-valves 10 and 7 in the first modification. The conduit 17 opens direct into the discharge-pipe 14, having a check-valve 30.

The main principle involved in my invention will be best understood by reference to the diagrammatic view, Fig. 7, which represents a small experimental apparatus constructed entirely of glass for the purpose of viewing the position and movements of the liquid therein. In this figure, 25 represents a horizontal compressed-air tube, and 26 a vertical liquid-discharge tube into which the air-tube 25 enters at 27. Said tube 26 is bent round at its lower end, and the upwardly-extending portion 28 is again connected with the air-tube 25 at a point 29 nearer the entrance of said tube 25. Now let the tube 26 be filled with water up to any level below the junctions 29 and 27 with the horizontal air-tube. Then let the experimenter blow gently into the tube 25. It will be found that the level of the water in the further branch 26 of the tube is higher than in the nearer branch 28. The explanation of this is obvious. When compressed air is flowing along a pipe and out therefrom into a region of less pressure, as the atmosphere, the velocity increases and the pressure falls as it approaches its outlet. The pressure at the point 29 is therefore greater than at the point 27. It is evident that the pressure on the liquids in the branches 28 and 26 are respectively equal to the pressure at the points 29 and 27, for until the water changes its level there is no

movement of air between the point 29 and the surface of the liquid in the branch 28, and, therefore, the pressures at the point 29 and at the surface of the liquid must be the same. 5 So also in the branch 26 the pressure at the point 27 must be the same as at the surface of the liquid. Since, therefore, the pressure at the point 29 is greater than at the point 27, the pressure on the liquid in the branch 28 is 10 greater than that in the branch 26, wherefore the water falls in the branch 28 and rises in the branch 26. In fact, if the experimenter blows vigorously, he can in this way drive nearly all the water out of the bent tube. 15 The effect is the greater when the tube 26 is of greater diameter than the tube 25, because then the air in entering the tube 26 at the point 27 so much more rapidly expands, and therefore falls so much lower in pressure, 20 causing a correspondingly greater difference between the pressures on the liquid in the pressure branch 28 and the eduction branch 26.

Considering now the operation of the pump shown in Figs. 1 and 2, it will readily 25 be seen that this pump will first operate as a double-acting suction-pump only until a sufficient amount of water has been sucked into each receiver to pass through the check-valves 10. Thenceforth it will act as a 30 force-pump on the principle illustrated by the experimental apparatus shown in Fig. 7. Each side then operates in turn as a force-pump, the other side at the same time acting as a suction-pump. To obtain a clear idea 35 as to how this apparatus, illustrated in Figs. 1 and 2, differs from an ordinary force-pump, let us return to the experimental apparatus illustrated in Fig. 7, and let us first imagine that the pipe 25 was completely 40 stopped between the points 29 and 27. Then evidently upon blowing into the pipe 25 all the air has to pass down the branch 28 and the whole of the water unmixed with air is forced upward through the pipe 26. 45 Now let us make the contrary supposition that the two points 29 and 27 are brought close together and the pipe 26 is of no greater diameter than the pipe 25. Under these 50 conditions the difference in the pressures at the points 29 and 27 is so small that there is substantially no difference of levels of the water in the branches 28 and 26. Then no water at all rises in the pipe 26, but only air passes upward therethrough. Between these 55 two extremes, then, when, on the one hand, all water and no air rises, and, on the other hand, all air and no water rises, it is possible to proportion the amounts of air and water to any desired ratio by properly adjusting the 60 degree of freedom with which the air passes from the point of junction with the pressure branch to the point of junction with the eduction branch, for upon this degree of freedom depends the difference of pressures at

the two points, upon which again depends 65 the difference of levels in the two branches. Two things which are necessary for the practical success of the apparatus, as shown, are also of advantage in increasing this difference of level. First, the check-valves 12 70 are necessary, because the movement is intermittent, alternately suction and compression, and the check-valves are necessary to allow of the suction; secondly, it is necessary that the water - discharge pipe 75 should be of greater diameter than the compressed-air pipe, the friction of water being so much greater than that of air. Both of these features of construction create a difference of pressure at the two junctions. The 80 principle of operation will be the same when there is a quantity of water in the pipe 9 above the check-valve 12. Suppose, for instance, that there are twenty feet of water above said check-valve and twenty-four feet 85 above the check-valve 10. Adding to these the weight of the atmosphere in its equivalent feet of water (thirty-two feet approximately) we have a head of fifty-two feet at the check-valve 12 and fifty-six feet at the 90 check-valve 10. Now suppose the maximum compressed-air pressure is a head of one hundred feet of water. The air escaping through the valve 12 will immediately fall in pressure to fifty-two feet of water and the 95 downward pressure on the check-valve 10 will still be fifty-six feet of water, while the upward pressure will be one hundred feet of water, so that the check - valve 10 will be lifted and water will pass upward. It is to 100 be remembered that at the beginning of each compression-stroke the water will stand in the pipe 3 at the level of the check-valve 10, making the pressure on the under side of the check-valve the same as that in the compressed-air pipe. Supposing now that the 105 amount of water in the pipe 9 has reached its maximum limit, which, assuming that the maximum limit of the compressed-air pressure is one hundred feet head of water, will be sixty-eight feet above the check-valve 10, (deducting thirty-two feet for the atmosphere,) an escape for the water from this pipe 9 must now be provided. The actual 110 height of the pipe 9 up to this point of escape 115 will depend upon the proportions of air and water. As has been already explained, if it is desired to increase the height to which the water is raised without increasing the pressure from the air-compressor this can only 120 be done by increasing the ratio of air to water. Assuming that such an escape has been provided, what will now be the *modus operandi*? The downward pressure on the check-valve 10 is one hundred feet of water, 125 which is equal to the maximum pressure; but owing to the valve 12 being above the valve 10—say four feet above—the pressure

at the valve 12 is ninety-six feet of water. Therefore compressed air will pass through the valve 12, which will displace an equal volume of water and will force water through 5 the escape at the top of the pipe 9, reducing the amount of water, and therefore the pressure at the check-valve 10, to less than one hundred feet of water and causing the check-valve 10 to rise and water to pass upward 10 thereat. The apparatus shown in Figs. 3 to 6 operates on the same principle. For instance, suppose that in the pipe 13 there are twenty feet of water above the check-valve 15 30 and twenty-four feet above the check-valve 23. Adding the weight of the atmosphere, this gives fifty-two feet pressure at the former point and fifty-six feet at the latter. As soon as the compressed-air pressure rises 20 above fifty-six feet of water the valve 23 will rise, for the pressure on the top of said valve 23 will not exceed fifty-six feet of water, because as soon as any air escapes through the 25 valve 30 it falls to a pressure of fifty-two feet of water, making a pressure on the top of the valve 23 of not more than fifty-six feet. The main advantage of this construction is that water can now be lifted to great heights by compressed air of comparatively 30 low pressure; but in addition this apparatus 35 is of greater efficiency than those using high pressure of compressed air, for there is not so much loss of energy by conversion into wasted heat. Thus by means of this apparatus not only can liquids be pumped from wells too deep to be successfully pumped out by the old methods; but even in comparatively shallow wells the efficiency of the present apparatus is greater. The expansion of the ascending strata of air in the pipe 40 9 serves to more rapidly force out the superincumbent strata of water, and thus lighten the load.

The main features of novelty of my invention which constitute its advance over the 45 prior art are as follows:

First, the ability to pump water to a great height with a comparatively low pressure—say to a height of one thousand feet with a pressure of one hundred pounds only and this 50 with only a single opening direct from the compressed-air pipe to the water-discharge pipe, said opening being just above the top check-valve of the receiver—is due to the fact that the size of the passage from the compressed-air pipe to the liquid-discharge pipe 55 is so regulated relatively to the height of said latter pipe and to the pressure of the compressed air that a sufficiently large proportion of air to the liquid is admitted into the discharge-pipe to distribute the liquid throughout the whole length of said pipe and interpose air therein to such an extent that the 60 weight of the entire amount of liquid therein shall not overbalance the pressure of the

compressed air. For instance, supposing 65 that the height of the discharge-pipe is one thousand feet and the pressure of the compressed air is one hundred pounds, which would ordinarily balance only about two hundred and twenty-five feet of water, then I 70 make the passage from the compressed-air pipe to the liquid-discharge pipe sufficiently large to admit a sufficient amount of air in proportion to the liquid that the whole amount of liquid in the one thousand feet of 75 pipe would, if allowed to fall into a solid column, be not more than two hundred and twenty-five feet in height.

A second important feature of my invention is the fact that, in conjunction with the receiver, the check-valve admitting the liquid to the receiver, the liquid-discharge pipe from the receiver, the check-valve between them, and the separate communications from the compressed-air pipe to the receiver 85 and to the liquid-discharge pipe, the latter passage is sufficiently large, free, and unobstructed that the compressed air can pass therethrough at each impulse in a sufficiently large proportion to the amount of liquid 90 forced by such impulse from the receiver into the discharge-pipe so as to form a solid column or piston of air in the liquid-discharge pipe, completely separating two such columns or pistons of liquid therein. By this 95 construction the air has its greatest efficiency in raising or driving the water before it as it expands and rises to the top of the discharge-pipe.

A third important feature of my invention is that I produce alternately positive and negative pressures in the compressed-air pipe. By a "negative" pressure is meant less than that of the atmosphere, which produces a suction in the receiver, thus drawing with certainty and rapidity the water into the receiver to fill the same to provide a fresh supply of water for the next impulse of compressed air. It is important that these impulses of compressed air should 100 follow each other quickly and uniformly, so as to keep the water in rapid upward motion to the top of the discharge-pipe. Otherwise, if the water is allowed to fall back work that has been done in raising the water is lost; also, 105 in sinking mines the water can be supplied to the receiver by suction only.

Fourthly, in the preferred form of my invention I provide two receivers and two branch discharge-pipes leading therefrom, 110 each having its check-valve therein, and a common discharge-pipe into which the branch discharge-pipes conduct, a compressed-air pipe leading to each receiver, and means for compressing the air alternately in 115 said pipes. By this means I obtain, as with the third feature of my invention above mentioned, a rapid succession of impulses in the

discharge-pipe, keeping the water in rapidly-
ascending movement.

I am aware that it has been proposed to elevate water to great heights, using comparatively low compressed-air pressure, by means of a receiver having upper and lower check-valves, a water-discharge pipe from said receiver, a compressed-air pipe leading into the receiver, and a series of branch pipes leading 10 from the compressed-air pipe to the discharge-pipe at substantially equal intervals all the way up to the top of said discharge-pipe. Thus in the system proposed, if compressed air of fifteen pounds pressure were 15 used, the lowest branch opening would be at a height of twenty-five feet above the top check-valve, and the other branch openings would be at distances of twenty-five feet apart successively upward. If a greater 20 pressure of the compressed air were used, the distance between the top check-valve and the branch openings would be proportionately greater, the distance in each case being substantially that to which the pressure of 25 the compressed air would raise a column of water. The principle of operation of this system was, in fact, as follows: The compressed-air pressure of, say, fifteen pounds, was used to raise a column of water from the 30 check-valve to a height of twenty-five feet, then another quantity of compressed air was admitted into the top of this column of water so raised to send it upward another twenty-five feet, then when the force of the compressed air in so raising the water was nearly 35 exhausted another supply of compressed air was admitted to raise it a further twenty-five feet, and so on up to the top of the discharge-pipe. This system, however, has, I believe, 40 never come into practical use. The mechanical difficulties in carrying out this system appear to be too great; and while the system might be successful theoretically after once started it is not easy to see how it could be 45 started, at least without an excessively high pressure of compressed air to begin with, as on account of the discharge-pipe being empty of water at the commencement of operation the compressed air would too readily flow 50 out thereinto, thus not providing sufficient pressure at the bottom. Furthermore, it was a special feature of this system that the air should enter the water-discharge pipe in minute streams or bubbles. Such streams 55 and bubbles will not have the same effect in raising the water as when the air is admitted in sufficiently large quantities to form a solid column of air filling the whole width of the pipe beneath the water, and thus positively 60 driving upward the water above it. In said system, again, no provision was made for a pair of receivers and branch discharge-pipes leading to a common discharge-pipe, nor could such provision have very well been

made on account of the difficulty of having a 65 double series of passages with check-valves connected with the discharge-pipes at intervals all the way from the receiver to the top. I am also aware that a system of elevating water has been used in which a succession of 70 alternating solid columns of pistons of air and liquid have been caused to ascend the discharge-pipe. Said columns have been formed by discharging compressed air into the open lower end of the discharge-pipe. No 75 receiver or check-valves were used in such a system, and it was therefore necessary to provide a head of water outside the discharge-pipe to two-thirds the height of said pipe—that is, to raise water one thousand feet the 80 lower end of the discharge-pipe would have to be continued to a depth of two thousand feet below the surface of the water. There are very few mines or wells where such a condition of affairs exist, and therefore that sys- 85 tem has a very limited application.

I claim—

1. In a liquid-impelling apparatus, a receiver, a check-valve admitting the liquid to the receiver, a liquid-discharge pipe from the receiver, a check-valve between them, a compressed-air pipe having separate communications with the receiver and with the liquid-discharge pipe, and means for producing alternately positive and negative pressures in 95 the compressed-air pipe, substantially as described.

2. In a liquid-impelling apparatus, a receiver, a check-valve admitting the liquid to the receiver, a liquid-discharge pipe from the 100 receiver, a check-valve between them, a compressed-air pipe having separate communications with the receiver and with the liquid-discharge pipe, the passage from the compressed-air pipe to the liquid-discharge pipe 105 being sufficiently large, free and unobstructed that the compressed air can pass therethrough at each impulse thereof in a sufficiently large proportion to the amount of liquid forced by such impulse from the receiver into the discharge-pipe as to form a solid column or piston of air in the liquid-discharge pipe, completely separating two such columns or pistons of liquid therein, substantially as described. 110

3. In a liquid-impelling apparatus, a receiver, a check-valve admitting the liquid to the receiver, a liquid-discharge pipe from the receiver, a check-valve between them, a compressed-air pipe having separate communications with the receiver and with the liquid-discharge pipe, the passage from the compressed-air pipe to the liquid-discharge pipe 115 being sufficiently large, free and unobstructed that the compressed air can pass therethrough at each impulse thereof in a sufficiently large proportion to the amount of liquid forced by such impulse from the receiver into the dis- 120

125

charge-pipe as to form a solid column or piston of air in the liquid-discharge pipe completely separating two such columns or pistons of liquid therein, and means for producing alternately positive and negative pressures in the compressed-air pipe, substantially as described.

4. In a liquid-impelling apparatus, a receiver, a check-valve admitting the liquid to the receiver, a compressed-air pipe leading to the receiver, means for compressing the air in said pipe, a liquid-discharge pipe leading from the receiver, and a check-valve between the discharge-pipe and the receiver, the compressed-air pipe opening into the discharge-pipe above the check-valve at a point relatively near the receiver, and the size of the passage from the compressed-air pipe to the liquid-discharge pipe being so regulated relatively to the height of said latter pipe and the pressure of the compressed air that a sufficiently large proportion of air to liquid is admitted into the discharge-pipe to distribute the liquid through the whole length of said pipe to such an extent that the weight of the entire amount of liquid therein shall not overbalance the pressure of the compressed air, substantially as described.

5. In a liquid-impelling apparatus, a receiver, a check-valve admitting the liquid to the receiver, a compressed-air pipe leading to the receiver, means for compressing the air in said pipe, a liquid-discharge pipe leading from the receiver, and a check-valve between the discharge-pipe and the receiver, the compressed-air pipe opening into the discharge-pipe at a point above said receiver, and the size of the passage from the compressed-air pipe to the liquid-discharge pipe being so regulated relatively to the height of said latter pipe and the pressure of the compressed air that a sufficiently large proportion of air to liquid is admitted into the discharge-pipe to distribute the liquid through the whole length of such pipe to such an extent that the weight of the entire amount of liquid shall not overbalance the pressure of the compressed air, and means for producing alternately positive and negative pressures in the compressed-air pipe, substantially as described.

6. In a liquid-impelling apparatus, a pair of receivers, check-valves admitting the liquid to the receivers, a compressed-air pipe leading to each receiver, means for producing alternately positive and negative pressures in the respective pipes, a branch liquid-discharge pipe leading from each receiver, a common discharge-pipe into which said branch pipes conduct, and a check-valve between each receiver and the discharge-pipe leading therefrom, the compressed-air pipe opening into the corresponding branch discharge-pipe above the check-valve, substantially as described.

7. In a liquid-impelling apparatus, a pair of receivers, check-valves admitting the liquid to the receivers, a compressed-air pipe leading to each receiver, means for compressing the air alternately in said pipes, a branch liquid-discharge pipe leading from each receiver, a common discharge-pipe into which said branch pipes conduct, and a check-valve between each receiver and the discharge-pipe leading therefrom, the compressed-air pipe opening into the corresponding branch discharge-pipe above the check-valve, the passage from the compressed-air pipe to the liquid-discharge pipe being sufficiently large, free and unobstructed that the compressed air can pass therethrough at each impulse thereof in a sufficiently large proportion to the amount of liquid forced by such impulse from the receiver into the discharge-pipe as to form a solid column or piston of air in the liquid-discharge pipe, completely separating two such columns or pistons of liquid therein, substantially as described.

8. In a liquid-impelling apparatus, a pair of receivers, check-valves admitting the liquid to the receivers, a compressed-air pipe leading to each receiver, means for compressing the air alternately in said pipes, a branch liquid-discharge pipe leading from each receiver, a common discharge-pipe into which said branch pipes conduct, and a check-valve between each receiver and the discharge-pipe leading therefrom, the compressed-air pipe opening into the corresponding branch discharge-pipe above the check-valve and relatively near the receiver, the size of the passage from the compressed-air pipe to the liquid-discharge pipe being so regulated relatively to the height of said latter pipe and the pressure of the compressed air that a sufficiently large proportion of air to liquid is admitted into the discharge-pipe to distribute the liquid through the whole length of said pipe to such an extent that the weight of the entire amount of liquid therein shall not overbalance the pressure of the compressed air, substantially as described.

9. In a liquid-impelling apparatus, a receiver, a check-valve admitting the liquid to the receiver, a liquid-discharge pipe leading from the receiver, and a check-valve between the discharge-pipe and the receiver, a compressed-air pipe and means for compressing the air therein, said compressed-air pipe opening into the discharge-pipe relatively near the receiver, and the size of the passage from the compressed-air pipe to the liquid-discharge pipe being so regulated relatively to the height of said latter pipe and the pressure of the compressed air that a sufficiently large proportion of air to liquid is admitted into the discharge-pipe to distribute the liquid through the whole length of said pipe to such an extent that the weight of the entire

amount of liquid therein shall not overbalance the pressure of the compressed air, and means for applying the force of the compressed air to force the liquid from the receiver into the discharge-pipe, substantially as described.

In witness whereof I have hereunto set my

hand in the presence of two subscribing witnesses.
